US00D990339S

(12) **United States Design Patent** (10) **Patent No.:** **US D990,339 S**
(45) **Date of Patent:** **** Jun. 27, 2023**

(54) **PLANT SENSOR DESIGN**

(71) Applicant: **Aabesh De**, Dover, DE (US)

D974,192 S * 1/2023 Larsen D10/56

* cited by examiner

(72) Inventor: **Aabesh De**, Dover, DE (US)

Primary Examiner — Antoine D Davis

(73) Assignee: **FloraSense Inc.**, Chicago, IL (US)

(74) *Attorney, Agent, or Firm* — Olav M. Underdal; IDP Patent Services

(**) Term: **15 Years**

(57) **CLAIM**

(21) Appl. No.: **29/788,440**

I claim the ornamental design for a plant sensor design, as shown and described.

(22) Filed: **May 27, 2021**

DESCRIPTION

(51) **LOC (14) Cl.** **10-04**

FIG. 1 is a left front perspective view of the plant sensor design embodying my design.

(52) **U.S. Cl.**

FIG. 2 is a front perspective view of the plant sensor design embodying my design.

USPC **D10/56**

FIG. 3 is a front elevation view of the plant sensor of FIG. 1.

(58) **Field of Classification Search**

FIG. 4 is a right side elevation view of the plant sensor of FIG. 1.

USPC D10/56

FIG. 5 is a left side elevation view of the plant sensor of FIG. 1.

CPC A01G 25/16; A01G 25/167; A01G 7/00;

FIG. 6 is a bottom plan view of the plant sensor of FIG. 1; and,

G01F 23/30; G01F 23/58; G08B 21/00;

FIG. 7 is a top plan view of the plant sensor of FIG. 1. Broken lines present in the drawings are for illustrative purposes only and form no part of the claimed design.

G08B 21/20; G01N 33/246; G01N 33/24;

G01N 29/036; G01N 2291/0212; G01N

27/223; G01N 27/041; G01N 27/048;

G01R 27/2623; G01R 27/20; G01R 27/14
